BY

ATTORNEY

UNITED STATES PATENT OFFICE.

OTTIS C. FLYNN, OF LEXINGTON, KENTUCKY.

BURGLAR ALARM.

Application filed March 25, 1922. Serial No. 546,681.

To all whom it may concern:

Be it known that I, OTTIS C. FLYNN, a citizen of the United States, residing at Lexington, in the county of Fayette and State of Kentucky, have invented new and useful Improvements in Burglar Alarms, of which the following is a specification.

This invention relates to a burglar alarm, the principal object of the invention being 10 to provide means for sounding an alarm if a window should be opened by a burglar.

Another object of the invention is to provide means whereby the device can be rendered inactive so that the window can be 15 opened without sounding the alarm.

This invention also consists in certain other features of construction and in the combination and arrangement of the several parts, to be hereinafter fully described, 20 illustrated in the accompanying drawings and specifically pointed out in the appended claim.

In describing my invention in detail, reference will be had to the accompanying 25 drawings wherein like characters denote like or corresponding parts throughout the several views, and in which:—

Figure 1 is a view of a window showing the invention in use.

30 Figure 2 is a sectional view through the sash of a window showing the invention in elevation.

Figure 3 is a sectional detail view showing the latch, its lever and a part of the bell 35 hammer.

In these views 1 indicates a bell, the hammer 2 of which is actuated by a spring 3, the spring being wound by rotating the bell part 4. The hammer is normally held 40 against movement by the head of the latch 5 but when said latch is raised by the latch lever 5' the hammer will be operated by the

spring to sound the alarm. A lever 6 is pivoted to the window casing and has a bent part 6' engaging the sash so that when 45 the sash is raised the lever will be moved and as the opposite end of the lever engages with the latch lever 5' this movement will cause said lever 5' to raise the latch and thus permit the spring actuated hammer to 50 strike the bell. The lever is made of stiff wire so that it can be pulled out of engagement with the latch lever which will leave the sash free to be opened without sounding the alarm.

55 It is thought from the foregoing description that the advantages and novel features of my invention will be readily apparent.

I desire it to be understood that I may make changes in the construction and in the 60 combination and arrangement of the several parts, provided that such changes fall within the scope of the appended claim.

What I claim is:—

An alarm attachment for windows comprising a bell rotatably secured to the window frame, a hammer pivotally secured within the bell and adapted to strike the edge thereof, a spring associated with the action of the hammer and adapted to be 65 wound by the rotation of the bell, a latch designed to hold the hammer in normal position, a lever secured to the latch, a pivoted lever secured to the window frame and normally positioned over the first mentioned 70 lever to hold said hammer inactive through the medium of the latch, a bent portion formed on the upper end of said pivoted lever and adapted to lie in the path of the sash of the window for the purpose 75 specified.

In testimony whereof I affix my signature.

OTTIS C. FLYNN,
